(57) **CLAIM**

The ornamental design for a wearable holder, substantially as shown and described.

DESCRIPTION

FIG. 1 is a front elevation view of a wearable holder, according to a first embodiment, embodying a design on a body; FIG. 2 is a rear elevation view of the wearable holder of FIG. 1 on the body;

FIG. 3 is a front elevation view of the wearable holder of FIG. 1;

FIG. 4 is a rear elevation view of the wearable holder of FIG. 1;

FIG. 5 is a perspective view of a side of the wearable holder of FIG. 1;

FIG. 6 is a perspective view of the other side of the wearable holder of FIG. 1;

FIG. 7 is a top view of the wearable holder of FIG. 1;

FIG. 8 is a bottom view of the wearable holder of FIG. 1;

FIG. 9 is an extended view of the components of the wearable holder of FIG. 1; and,

FIG. 10 is a front perspective view of the wearable holder according to a second embodiment.

The broken lines shown are for illustrative purposes only and form no part of the claimed design.
